United States Patent Office.

WILLIAM W. WAIT, OF RICHMOND, INDIANA.

Letters Patent No. 100,569, dated March 8, 1870.

IMPROVED BED-BOTTOM.

The Schedule referred to in these Letters Patent and making part of the same.

To whom it may concern:

Be it known that I, WILLIAM W. WAIT, of Richmond, Wayne county, Indiana, have invented a new and improved Invalid and general purpose Bed-Bottom, of which the following is a specification.

The object of my invention is to provide a simple and durable bed-bottom, that shall be applicable to any bedstead, and which, while equal to the best for ordinary use will be especially well adapted to the use of invalids.

To this end I employ an adjustable frame hinged to the principal frame of the bottom in such a manner that it may be elevated, thereby raising the head and shoulders of the occupant.

The first part of my invention consists in the peculiar construction and arrangement of the pawls that support the adjustable frame and the rod to which they are attached, the latter being fixed in the principal frame while the pawls engage in racks attached to the adjustable part.

The second part of my invention relates to certain cheap and convenient devices, as will be hereinafter described, for preventing lateral motion in the slats while allowing a free vertical motion.

My invention further relates to the arrangement of the lever and other devices for operating the adjustable frame, and to the general combination of parts, as will be described.

Description of Drawings.

Figure 1 is a perspective view of a bed-bottom embodying my invention represented as placed upon a bedstead ready for use.

Figure 2 is a plan view of the bottom removed from the bedstead.

Figure 3 is a longitudinal vertical section of the same.

Figure 4 is a detached view of the lever and pawls with the rod to which they are attached.

Figure 5 is a detached view of a portion of the slats, showing the devices for guiding the ends of the same.

General Description.

I provide for my bed-bottom a rectangular frame composed of the side and end rails A A' and B B', the horizontal rails or bearers C C' C", and the cross-pieces D.

The transverse slats E E', &c., are supported on

helical springs that rest on the horizontal rails C C' C"; only the slats that support the greatest weight of the body are supplied with springs at the center, as shown at R' R² R³.

These springs R' R² R³ are similar to all the others, and by their use the slats are graduated very nearly in proportion to the weight imposed.

The slats, E E', &c., are allowed vertical play, and are guided at their ends by pins g g placed one on either side of the slat, or otherwise, by a single pin, I, placed at each end of the slat and fitting a notch, U, in said slat.

These pins may be detached from the rails A A', or they may be semicylindrical and glued to those rails, as shown in fig. 5.

In order to prevent an unequal elevation of the slats E E', &c., a ledge is formed of the pieces J J that are placed on the rails A A', and project over the ends of the slats.

The adjustable or head-raising part consists of an inner frame whose sides a a' c c' correspond to the sides A A' C C' of the main frame to which they are united by means of hinges or pivots P P.

These hinges may be placed at the top or bottom of the rails or at any intermediate points.

The adjustable frame a a' c c' is supplied with springs and slats similar to those of the main frame and correspondingly lettered.

G represents a rod of iron to which the pawls K K are rigidly attached.

The rod G is journaled in the main frame A A', and is provided with a lever, N, by means of which it is revolved.

The racks L L are attached to the under side of the rails a a' of the adjustable frame, the latter being held in any required position by the pawls K K that engage with said rack.

Having thus fully described my said invention,

I claim—

1. The rod G journaled in the rails A A', the lever N, and pawls K K, in combination with the slats E and hinges or pivots P P, as described.

2. The semicircular guide-pins I, the notches U, and the springs R, arranged and operated as described, for the purposes and in the manner set forth.

WILLIAM W. WAIT.
